PAPER CONTAINER WITH NONBUCKLING FLANGED HEAD AND PROCESS OF MAKING SAME

Filed Jan. 26, 1924

UNITED STATES PATENT OFFICE

ARLINGTON MOORE, OF WORCESTER, MASSACHUSETTS

PAPER CONTAINER WITH NONBUCKLING FLANGED HEAD AND PROCESS OF
MAKING SAME

Application filed January 26, 1924. Serial No. 638,708.

My invention relates to a paper container with non-buckling flanged head and process of making same. The term "paper" is used herein for convenience to designate paper or other fibrous sheet materials having characteristics similar thereto.

When flanged heads of paper are drawn from a continuous blank or disc the radius of the flanged head is reduced from that of the blank by substantially the height of the flange, and the diameter is reduced to an extent substantially equal to twice the height of the flange. Thus the material at and toward the margin of the flange, having been compressed in the formation of the flange to occupy only a fraction of its original diameter, has a tendency to expand.

When such a head is introduced into the interior of a container preparatory to being formed into parallel interlocked folds with the wall of the container body or shell, this tendency of the flange margin toward circumferential elongation or expansion is manifested by an inward buckling. This inward buckling of the flange when it occurs at one or more places in the flange, interferes seriously with and may serve to prevent the successful formation of the head flange into the parallel interlocked folds with the body wall, which is required to produce a satisfactory hermetic seal by being subsequently formed into a substantially welded seam of permanent gage dimension by application thereto of consolidating pressure, such for example as a pressure of three to five tons per square inch. This difficulty, while appearing to some extent in the application of heads to cylindrical paper bodies, is particularly troublesome in case of the application of flanged heads to tapered bodies where the normally right angle flange is brought inwardly still further on an angle to conform with the angle of the taper container body wall.

I have found that when the margin of the flange is made of non-continuous material, as for example, when the paper head blank is notched, preliminarily to flanging, with preferably substantially V-shaped notches preferably equally spaced about the outer margin of the blank, these difficulties can be elimi-

nated, and furthermore the flange may be drawn or made considerably deeper than would otherwise be possible. Such an extra deep flange is a feature of special utility where a higher multiplicity of parallel fold formations are made use of in making up the interlocked parallel folded seam portion.

In the accompanying drawings I have shown embodiments of the invention, but it is to be understood that same are for illustration only and not for imposing limitations on the invention, changes and modifications thereof being within my invention, so long as same are included within my claims, by which the scope of the invention is defined.

In said drawings, Fig. 1 is a side view of a taper paper container or firkin partly broken away to show in section a bottom head interlocked in a consolidated parallel folded seam with the body wall. Fig. 2 is a central vertical sectional view showing the introduction of a flanged head into a cylindrical body wall. Fig. 3 is a plan view of a circular notched disk for forming a flanged container head. Fig. 4 is a fragmentary vertical central sectional view showing the introduction of a flanged head part way into a tapered container body (such as the body of Fig. 1) to form the bottom head thereof. Fig. 5 is a view similar to Fig. 4, showing the flanged head pushed further down into position for interfolding with the taper container body or shell. Fig. 6 is a fragmentary cross-sectional view showing the body wall and head flange of Fig. 2 interlocked in parallel folds preparatory to completion of the closure seam by application thereto of consolidating pressure. Fig. 7 is a cross-section similar to Fig. 6, but showing the closure seam after application thereto of consolidating pressure, and Fig. 8 is a view similar to Fig. 7, but showing a closure seam made up of an increased number of parallel folds.

The head blank 10 (Fig. 3) preferably of generally circular form, but which may be of other forms, and which is to be flanged along the flange line indicated at 12, is provided with a series of peripheral notches 14, which are preferably of substantially V-form, as shown, and preferably spaced sub-

stantially evenly about the margin of the blank and having their apices extending inwardly, as shown. When the head is flanged as shown in Fig. 4 along flange line 12, the notches 14 are partially closed, as indicated at 16, Fig. 4, this being due to two causes, one, the natural spreading of the fiber of the paper during the flanging operation to occupy the open space of the notches, and second, the reduction in diameter from substantially the original periphery of the blanked out head 10 to a reduced diameter substantially the same as the diameter of flange line 12. It is sufficient for ordinary purposes that the notches 14 extend but part way inwardly from the edge of the blank 10 to the fold line 12. The particular depth of notch will, of course, vary with a number of various differing factors, as the thicknesses of stock, depth of flange, depth of finished seam desired and number of folds in the seam.

The flanged discs 18 so formed have many uses and can be used to advantage in many places. In Figs. 1 and 5 such flanged disk 25 is illustrated to form the bottom end or head 20 of a container or firkin comprising a tapered tubular body 22. When flanged discs that are not notched in accordance with my invention are introduced into the tapered 30 tubular bodies to form containers they are liable to buckle in a number of places due to the squeezing together of the material of the flange as it is pushed down into the tapered container body, but where the flanged 35 heads are notched as herein described, it is possible to introduce them into a tapered tubular body without any buckling, the forces which would otherwise produce buckling being effective only to bring the walls or 40 edges of the notches substantially close together as indicated at 24, Fig. 5. When the flange 26 and body wall 28 are interlocked together in parallel folds, as, for example, five folds in the form shown in Fig. 6, (Fig. 45 6 is a detail for the form of Fig. 2, which shows a top head, but the position is merely reversed for a bottom head, as will be plain from Fig. 1) it becomes possible to produce the necessary turning over of head flange 50 and body wall margin into parallel folds, without any of the interference which would exist to such turning over in case the flange had buckled, and upon finally fabricating or consolidating the several thicknesses together by application of consolidating pressure, a consolidated and interlocked parallel fold joint, such as indicated at 30, Fig. 1 may be obtained.

Flanged heads made as described are also 60 useful in other connections, as, for example, in Fig. 2 I have shown the application thereof in connection with the heading of cylindrical containers 32 having cylindrical tubular body walls 34. In such containers it 65 is preferable to have the flanged heads 36

when pushed into the container body preliminary to the interlocking and fabricating steps of an external diameter slightly larger than the internal diameter of the shell. For example, in shells of four inches in diameter I have found it desirable to make use of flanged heads 36 having an outside diameter of ten to twelve one-thousandths of an inch larger than the inside diameter of the shell 32. When flanged heads not notched in accordance with the present invention are so introduced, it frequently happens, due to the tendency of the flanged material to expand and due to compression exerted thereon by the shell into which it is pushed, that one or more inward bulges will be formed in the flange. When this happens the folding and fabricating together of the flange and the body wall are prevented at the points of buckling, and the container produced is crushed, instead of fabricated, at the point of buckling, and must be discarded. When, however, the blank has been preliminarily notched in accordance with the present invention, these difficulties do not arise, and it becomes readily possible to secure a proper fabricated joint, and the body walls and flange may be folded together in parallel folds as in Fig. 6, and later the complete fabrication thereof together completed as 95 in the showing of Fig. 7.

When extra deep flanges are to be drawn on the heads in order to be fabricated, for example, in making a doubly folded joint, as the shown seven fold joint 40 in Fig. 8, the use of notched head forming blanks becomes a matter of specially great utility. The flange which can be drawn on an ordinary unnotched paper head of a given thickness is limited to a very moderate width or depth by 100 reason of the embrittling effect which is produced by the application of unduly high compression forces to the relatively thin bodied material of the flange. If it be attempted, for example, to convert say a nine inch diameter unnotched disk of paper stock of about .0020" thickness into a flanged head having a diameter of about three inches and a flange depth of about three inches, and to have the flange of substantially uniform thickness, it 105 will be found that, if such operation were otherwise practicable, the stock at the outer margin of the flange would have to be so highly calendered and so tremendously compressed within the narrow space available 110 that the fibre strength would be broken down and the material so weakened and embrittled as to break at the slightest touch. With the notched blanks, a very marked increase in 115 depth of flange can be obtained without such resultant embrittling of the flange margin, and the flanges produced are of relatively high cohesion and can be formed in strong parallel folds with the body walls, it being 120 possible in this way to secure a number of 125 130

such folds considerably in excess of the number possible with an unnotched flange.

It will be seen that in each of the forms shown the split up or notched free edge or margin of the flange is, so to speak, turned inside or imbedded or buried within the complete interlocked joint, so that there can be no tendency to come apart or to exhibit what might be referred to as a tendency to unravel as might be present in a construction in which the split up or notched edge is exposed as a raw edge. Thus the portions 42 in Figs. 6 and 7 and 42' in Fig. 8 show the notched part of the flange so imbedded or buried in the seam, the section being taken along lines including the closing lines 24 of the flange notches, as shown at *a—a*, Fig. 2.

I claim:

1. A seam for paper containers comprising a body wall, and a flanged head folded together in parallel interlocked folds, the flange having notches in the margin thereof.

2. The process of forming a paper device which consists in taking a tubular-body member and a head having a notched flange, assembling said tubular member and said head with the notched flange thereof engaging the wall portion of said tubular member, and folding the contiguous portions of said tubular member and said notched flange together in interlocking relation.

3. The process of forming a paper device which consists in taking a tubular member and a head having a notched flange, assembling said tubular member and said head with the notched flange thereof engaging the wall portion of said tubular member, folding the contiguous portions of said tubular member and said notched flange together in interlocking relation, and subjecting the seam thus formed to high pressure.

4. The process of forming a paper device which consists in taking a blank, forming a series of notches therein around the periphery thereof, forming a flange in said blank by deforming the same about a line spaced inwardly from the inner ends of the notches and drawing the opposing edges of said notches towards each other, whereby to produce a head having a flange including a substantially continuous inner portion and an interrupted outer portion, taking a tubular member, assembling said tubular member and said head with the notched flanged portion thereof engaging the wall portion of said tubular member at one end, and folding said contiguous portions together and pressing the same into interlocking relation.

5. A paper device comprising a tubular member, a head closing an end of said tubular member and having a notched flange portion engaging the adjacent wall portion of said tubular member; the contiguous portions of said tubular member and said head being folded together in interlocking relation.

6. A paper device comprising a tubular member, a head closing an end of said tubular member and having a notched flanged portion engaging the adjacent wall portion of said tubular member; the contiguous portions of said tubular member and said head being folded together and the notched flanged portion of said head being disposed within the folds of said wall portion.

7. A paper device comprising a tubular member, and a head closing an end of said tubular member and having a flange including a substantially continuous inner portion and a notched outer portion in engagement with the adjacent wall portion of said tubular member; the contiguous portions of said tubular member and said head being folded together in interlocking relation.

8. A paper device comprising a tubular member and a head closing an end of said tubular member and having a flange including a substantially continuous inner portion and a notched outer portion in engagement with the adjacent wall portion of said tubular member; the contiguous portions of said tubular member and said head being folded together and compressed into interlocking relation, and the folded portions of said flange being enclosed by the contiguous folded portions of said tubular member.

9. The process of forming end seams in paper containers, which comprises forming a series of substantially V-shaped relatively narrow notches in about the periphery of an end disk for the container, flanging said disk about a line disposed inwardly from the inner ends of the notches, whereby a drawn flange having a continuous inner portion is produced, and the notches are substantially closed at and near the outer flange margin, introducing said flanged disk into a container body with the flange margin directed outwardly and lying against the interior of the body wall, infolding the body margin and flange margin into a plurality of folds, whereby the edges of both the body wall and the flange are enclosed, and applying consolidating pressure to the infolded parts, whereby same are brought into substantial parallelism and the folds parts are consolidated into a seam of substantially permanent dimension of high strength.

In testimony whereof, I have signed my name hereto.

ARLINGTON MOORE. 120
